Emil G. Gassen,

Inventor:

By Charles Turner Brown,
Attorney.

UNITED STATES PATENT OFFICE.

EMIL G. GASSEN, OF SIOUX CITY, IOWA.

SAFETY-FAUCET AND WATER-CONTROLLING CONNECTION.

SPECIFICATION forming part of Letters Patent No. 696,731, dated April 1, 1902.

Application filed December 9, 1901. Serial No. 85,239. (No model.)

To all whom it may concern:

Be it known that I, EMIL G. GASSEN, a citizen of the United States, and a resident of Sioux City, in the county of Sioux and State of Iowa, have invented certain new and useful Improvements in Safety-Faucets and Water-Controlling Connections for Water-Supply Pipes in Dwellings and other Places, of which the following, when taken in connection with the drawings accompanying and forming a part hereof, is a full and complete description, sufficient to enable those skilled in the art to which it pertains to understand, make, and use the same.

The invention relates to faucets to water-supply pipes wherein the water is forced through the supply-pipes and through the faucet when the water is turned on and the faucet is open and to means to turn such water on and off.

The object of this invention is to obtain a safety water-faucet and water-controlling connection to be placed and used as stated—that is, a faucet and water-controlling connection by the use of which the freezing of water in the pipes during the winter months will be obviated.

An additional object of this invention is to obtain an apparatus of the kind named by means of which the water obtained from the faucet will be cool and palatable; and a further object of the invention is to obtain an apparatus by means of which the likelihood of lead-poison, where lead pipes are used in plumbing a house, is largely obviated.

The mechanisms by means of which I embody the invention herein set forth, described, and claimed are illustrated in the drawings referred to, wherein—

Figure 1 is a front elevation of a safety-faucet and water-controlling connection and rod. Fig. 2 is a vertical sectional view of the water-controlling rod, the upper end of the safety-faucet plunger, and a modification of the connection between such safety-faucet and the plunger-rod. Fig. 3 is a horizontal sectional view on line 3 of Fig. 2 viewed in the direction indicated by the arrows. Fig. 4 is a top plan view of the water-controlling rod and the connection adjacent thereto on line 4 of Fig. 2 viewed in the direction indicated by the arrow; and Fig. 5 is a vertical

sectional view of the safety-faucet illustrated in Fig. 1, the upper end of the plunger-rod of such faucet being also shown in Fig. 2 of 55 the drawings.

A reference-letter applied to designate a given part is used to indicate such part throughout the several figures of the drawings wherever the same appears.

A is the faucet of the apparatus. Faucet A comprises a shell provided with delivery end a and plunger-rod end a' , plunger-rod a^2 , (preferably of two parts pivotally connected, as at a^3), plug a^4 on rod a^2 , spring a^5 interposed between disk a^6 and the shell of the faucet, (such disk a^6 is rigidly secured on plunger-rod a^2), packing a^7 a^8 , and nut a^9 . A' is the water-supply pipe to which faucet A is attached.

B B are screw-threaded connecting-rods by means of which connection C (and connection C^2 , Fig. 2) is attached to the faucet A. The connection C has a hole therethrough, through which rod D, controlling the admission of water from the street-mains or other source of water-supply to the house-pipes, passes. The position of the connection C on the rod D is controlled in the construction illustrated in Fig. 1 by nuts C' C' and in the 80 construction illustrated in Figs. 2, 3, and 4 by the fastening-clip I.

D' is the key to rod D, by means of which key the rod is turned either to admit water to the house-pipes or to shut water from the 85 house-pipes and permit the water contained therein to flow to waste therefrom in the ordinary way.

C^2 is a modification of the connection from the connecting-rods B B to connecting-rod D 90 (see Figs. 2, 3, and 4) and may consist of a tube.

E is a cam-lever pivotally mounted in connection C^2 on pivot e in such manner that when the handle e' thereof is in the position 95 illustrated in Fig. 2 of the drawings the plunger-rod a^2 of faucet A is depressed, and the plug a^4 of such faucet A is thereby forced off its seat, so that water will flow from the house-pipe A' through the faucet and be discharged 100 at end a thereof. The connection C, Fig. 1, is attached to the faucet A and adjusted by the nuts b b , so that the plunger a^2 is depressed in the same manner as by the placing of the

lever e^2 of cam E in the position illustrated in the modification shown in Fig. 2 of the drawings.

e^2 is a recess in the cam E.

5 F is a washer on one of the rods B B and a stop for cam E.

G is a longitudinally-movable rod held in place in connection C² by staples g g and adjustable by means of handle G', attached to such rod G and extending through slot g' in such connection C².

H is a cam secured on rod D by pin h to turn therewith, and h' h' are shoulders on cam H.

15 The rod G is movable longitudinally, so that one end thereof may be in recess e^2 of cam E, at which time the other end thereof is adjacent to cam H, but not in contact therewith, as is illustrated in Fig. 2 of the drawings, or such rod G may be moved out of the recess in cam E and in front of shoulder h' of cam H. When rod G is in the first-named position, (in the recess in cam E,) cam E is locked in the position thereof illustrated in Fig. 2 of the drawings, and the plunger a⁴ on plunger-rod a² of faucet A is maintained off its seat against the resiliency of spring a⁵ and in position so that water may flow through the faucet. When rod G is moved longitudinally from the position thereof illustrated in Fig. 2 of the drawings into the position illustrated in Fig. 3 of the drawings, so as to be in contact with one of the shoulders h' of cam H and out of recess e^2 in cam E, the cam

35 E can then be moved so that plunger-rod a² of faucet A will be moved by spring A⁵ into substantially the position thereof illustrated in Fig. 5 of the drawings, at which time plug a⁴ is closed on its seat. To move rod G longitudinally into such position, releasing cam E and locking cam H, rod D must first be turned so as to shut water from the street-pipes entering the house-pipe, and so as to permit the water in the house-pipes to flow to waste,

45 and before water can again be turned on the house-pipes the lever e^2 of cam E must again be brought into substantially the position illustrated in Fig. 2 and the rod G must be moved longitudinally into the recess e^2 of cam

50 E. Connection C being secured in place so that the faucet A is open, (plug a⁴ is off its seat,) the handle or key D' is turned to admit water from the street-mains to the house-pipe or to prevent water from so entering, as de-

55 sired. When handle or key D' is turned to permit water to flow from the street-main to the house-pipe, water will flow through the faucet A, and the only way to stop such flow is to turn the key D' to shut the water off from the

60 house-pipe A' and to permit the water in the house-pipe to flow to waste. If any accident happens to the rod D, so that water cannot be shut from the house-pipe A', the connection C may be disconnected from the faucet by

65 turning the nuts C' C' on rod D and also the nuts b b on the connecting-rods B B to release the rod a² from its retracted position, permit-

ting plug a⁴ to seat, and thereby stop the flow of water.

In the modification illustrated in Figs. 2, 3, and 4 of the drawings the connection C² is permanently attached to faucet A by means of connecting-rods B B and nuts thereon, and in this construction in case when the rod B is turned to shut water off from the house-pipe A' and by breakage or otherwise the turning of the rod does not stop the flow of water through the house-pipe A' and faucet A the longitudinally-movable rod G may be moved out of the recess in cam E and in front of the cam H, and thereafter cam E can be turned to permit the plug a⁴ to come to its seat. In this modification when plug a⁴ is seated the rod D, together with cam H thereon, cannot be turned to admit water into the house-pipe A' until longitudinally-movable rod G is moved from in front of cam H, and to move such rod G away from in front of the cam H it is necessary to bring cam E into substantially the position thereof illustrated in Fig. 2 of the drawings and then move rod G longitudinally into the recess e^2 of such cam E. Provision is thus made for preventing flooding of the house when the turning of the rod D to shut water off from the house-pipes does not accomplish the desired result.

Having thus described my invention, what I claim as new, and desire to secure by Letters Patent, is—

1. In a safety-faucet and water-controlling connection, a faucet, connected to the water-supply house-pipe, a rod provided with a handle by means of which water can be turned into and shut off from the house-pipe, and a connection between the faucet and the rod, such connection arranged to hold the valve-plug of the faucet off from its seat; substantially as described.

2. In a safety-faucet and water-controlling connection, the combination of a faucet connected to the water-supply house-pipe, a rod whereby water may be turned into and shut off from the house-pipe, a connection between the rod and the faucet, mechanism in such connection to maintain the valve-plug of the faucet off from its seat when the rod is turned to admit water to the house-pipe and means to release such mechanism when the rod is turned to shut water off from the house-pipe; substantially as described.

3. In a safety-faucet and water-controlling apparatus a house-pipe and a faucet consisting of a casing provided with a valve-seat and a discharge-outlet, a longitudinally-movable rod in the casing, a valve-plug on the rod and a spring yieldingly holding the valve-plug on its seat, in combination with a rod movable to turn water off from and to admit water to the house-pipe and a connection between the rod and the faucet, such connection attached to the faucet to depress the longitudinally-movable rod and maintain the valve-plug off its seat; substantially as described.

4. In a safety-faucet and water-controlling connection, the combination of a faucet to the water-supply house-pipe, a rod whereby water may be turned into and shut off from the house-pipe, and a connection between such rod and the faucet such connection consisting of a pipe or tube, a cam in such pipe or tube, such cam provided with a recess and means to turn the cam, a longitudinally-movable rod in the pipe or tube and a cam on the rod controlling the admission of water to the house-pipe, the cams, longitudinally-movable rod in the pipe or tube and the plunger-rod of the faucet so related that when the longitudinally-movable rod is in the recess of the cam in the tube or pipe the faucet is open and the rod controlling the admission of water to the house-pipe may be turned to admit

water into the house-pipe or to shut water off from the house-pipe, as desired, and when 20 such longitudinally-movable rod is in front of the cam on the rod controlling the admission of water to the house-pipe it is out of the recess in the cam and such rod controlling the admission of water to the house-pipe 25 is in position to permit the water in the house-pipe to run to waste and such rod cannot be turned to admit water to the house-pipe, and at such time the cam in the pipe or tube can be turned to open or close the valve of the 30 faucet, as desired; substantially as described.

EMIL G. GASSEN.

In presence of—

CHARLES TURNER BROWN,
CORA A. ADAMS.
